[57] CLAIM

The ornamental design for a fireplace heater, as shown
and described.

DESCRIPTION

FIG. 1 is a front elevational view of the fireplace heater
showing my new design;

FIG. 2 is a plan view of FIG. 1;

FIG. 3 is a side elevational view taken from the right
side of FIG. 1 on a reduced scale, the left side being a
mirror image of the right side shown herein;

FIG. 4 is a rear elevational view of FIG. 1 on a reduced
scale; and

FIG. 5 is a bottom plan view of FIG. 1 on a reduced
scale.

FIG. 1

FIG. 2

FIG. 3

FIG. 4
